Fig. 3.

Orrin Newton, of Pittsburgh, Pa.
Letters Patent No. 732. Dated Oct 9th 1855.

The schedule referred to in these Letters Patent and making part of the same

To all whom it may concern:

Be it known that I, Orrin Newton, of Pittsburgh,
in the county of Allegheny and State of Pennsylvania, have invented
or produced, a new and original design for Jugs or covers for
jugs, and I do hereby declare the following is a full & exact
description of the same, reference being had to the annexed
drawings forming part of this Specification, wherein.

Figure 1. is a perspective view of my improved jug top, with
the lid closed.

Figure 2. is the same with the lid open.

Figure 3. is a plain vertical section thereof.

My improved jug top is designed to be made of white metal
or other suitable material, and is, as usual, in two parts; the
neck α , and the lid or cover b , the neck is cylindrical for
about one half of its height, with a plain or ornamental band
around its base. The upper half of the neck piece flares out,
still preserving its circular shape, excepting at the under
lip c , which projects from neck piece, & is of the shape shown
in the drawing. The under lip c , as well as the upper lip
 e , on the cover, are made separate from the piece with which
they are connected, being soldered on after the neck piece
and cover are made. The neck piece (without the lip c .) is perfectly
circular, & may readily be turned in a lathe. The hinge d , is
placed a little in from the circumference toward the centre of
the cover & does not project outside of the circumference opposite to
the lip. The upper edge of the neck, (as well as its lower edge) is

in parallel planes, excepting the under lip ϵ , which, when attached to the neck piece rises slightly above the level of the rest of the neck piece.

The cover or lid is circular, excepting at the upper lip ϵ . The upper lip, on the cover, does not however interfere with the pattern, but projects from the circumference of the lid, being soldered on after it is turned. The under surface of the cover, and upper lip ϵ , fit closely on the upper surface of the neck piece and lower lip ϵ . The cover is circular (excepting where the upper lip ϵ , projects as a cover for the lower lip ϵ .) & for a small distance from the circumference towards the centre is flat. Near the centre is an arch, or dome, which is surmounted by a handle f , for convenience in raising the lid. The contour of the cover is shown clearly in section, in figure 3. This arching of the lid or cover is designed not only for ornament but to give strength to the lid, preventing its being easily bent, & thus securing its fitting closely on the upper edge or surface of the neck piece. The usual shape of the cover corresponding of course with the upper surface of the neck piece, is a curved plane surface which is much more difficult to make, & being liable to be easily bent, it is difficult to keep it in order, so as to fit closely as a cover, to the neck piece. By constructing the cover with an arched centre the difficulty is obviated as it is not liable to become bent out of shape. Another great advantage of the circular shape of the neck piece & cover is, that it may readily (excepting the lip & handle) be turned in a lathe, & thus made much more easily & for cheaper.

Having thus described my improved design for a Jug cover, what I claim as my invention, is making metallic covers and pitchers of the shape and pattern shown in the drawings, and hereinbefore described.
